United States Patent Office

Des. 211,989
Patented Aug. 20, 1968

211,989

INSECT CAGE

Daniel Angelo Rodolfo, 29157 Birchrest Drive, Warren,
Mich. 48093, and Robert Rodolfo, 23815 Almond,
East Detroit, Mich. 48021

Filed June 3, 1966, Ser. No. 2,547

Term of patent 14 years

(Cl. D22—19)

FIG. 1 is a front elevation view of an insect cage, showing our new design;

FIG. 2 is a side elevation view thereof, as seen from line 2—2 of FIG. 1;

FIG. 3 is a rear elevation view thereof, as seen from line 3—3 of FIG. 2;

FIG. 4 is a top plan view thereof, as seen from line 4—4 of FIG. 1;

FIG. 5 is a bottom plan view thereof, as seen from line 5—5 of FIG. 3;

FIG. 6 is a second embodiment of the insect cage showing our new design;

FIG. 7 is a side elevation view thereof, as seen from line 7—7 of FIG. 6;

FIG. 8 is a rear elevation view thereof, as seen from line 8—8 of FIG. 7;

FIG. 9 is a top plan view thereof, as seen from line 9—9 of FIG. 6; and

FIG. 10 is a bottom plan view thereof, as seen from line 10—10 of FIG. 8.

We claim:

The ornamental design for insect cage, as shown and described.
